UNITED STATES PATENT OFFICE

HAROLD L. WATSON, OF EAST ST. LOUIS, ILLINOIS

WELL SCREEN

Application filed April 6, 1931. Serial No. 528,191.

This invention relates to a well screen and it consists in the novel features hereinafter described and claimed.

An object of the invention is to provide a screen made up of a series of interlocking sections each section having openings through which water may pass but which will prevent the passage of sand. The sections may be disposed longitudinally of the wall tubing or may surround the tubing as desired. Each section consists of a strip having an intermediate channel portion formed therein, the wall of said channel portion being provided with openings. One side wall of the channel portion is extended into a scroll and the other side wall of the channel portion extends into a double fold and then terminates in a scroll. The scroll at the edge of one section is adapted to interlock with the scroll at the edge of the adjacent section in the formation of the screen.

In the accompanying drawings:—

Figure 1 is a horizontal sectional view of a tubing with the screen applied. Figure 2 is a side elevational view showing a tube with the screen applied thereto and extending longitudinally thereof.

Figure 3 is a perspective view of one of the sections of the screen.

Figure 4 is a side elevational view of a tubing showing the screen sections surrounding the same.

The screen consists of a number of sheet metal sections 1 each section having an intermediate channel portion 2 formed therein and the wall of said channel portion being provided with openings 3. One side wall of the channel portion 2 is extended into a scroll edge 4 and the other side wall of the channel portion 2 is extended into a facing 5 which is folded back upon itself as at 6 and then extended into a scroll edge 7. The scroll edge 7 of one section interlocks with the scroll edge 4 of the next adjacent section and vice versa.

It is apparent that when the sections are applied to the tubing in the form of a screen that the water may pass through the openings 3 but the openings are of such diameter

as to prevent sand from passing through the screen.

Having described the invention what is claimed is:—

1. A well screen comprising sections each section having an intermediate channel portion formed therein, each channel portion having a wall provided with openings, one of the side walls of the channel portion being extended into a scroll edge, the other side wall of the channel portion being extended into a facing portion which is bent back upon itself and the folded back portion being extended into a scroll edge. 55

2. A well screen comprising sections of sheet metal each section having an intermediate channel portion formed therein and extending longitudinally thereof, the wall of said channel portion having openings, one of the side walls of said channel portion being extended into a locking scroll, the other side wall of the channel portion being extended into a facing portion which is folded back upon itself and the said folded back portion being extended into a locking scroll 75 edge. 60

In testimony whereof I affix my signature.

HAROLD L. WATSON.
